UNITED STATES PATENT OFFICE.

MARCY J. DU BOIS, OF PASSAIC, NEW JERSEY, ASSIGNOR TO PASSAIC METAL WARE COMPANY, OF PASSAIC, NEW JERSEY, A CORPORATION OF NEW JERSEY.

CONTAINER.

1,303,465.

Specification of Letters Patent. Patented May 13, 1919.

Application filed December 27, 1917. Serial No. 209,020.

To all whom it may concern:

Be it known that I, MARCY J. DU BOIS, a citizen of the United States, and resident of Passaic, in the county of Passaic and State 5 of New Jersey, have invented certain new and useful Improvements in Containers, of which the following is a specification.

My invention relates to improvements in the class of containers commonly called 10 boxes, cans, or tin cans, which are provided with removable covers at their open ends, but when such cans are made of rectangular shape, their side walls are liable to be pressed in adjacent to the mouth of the container, whereby the contents may sift and 15 leak through the joint between the flange of the cover and the wall of the container.

The object of my invention is to stiffen or 20 reinforce the walls of the container adjacent to the open mouth thereof, in a simple and cheap manner and without interfering with the filling or emptying of the container, whereby to resist pressing in of the wall or 25 walls adjacent to the cover, so as to overcome the objection above referred to with regard to the leaking of the contents from 30 the container.

In carrying out my invention I provide 35 a container having an open mouth, and a cover therefor, with a reinforce within the container adjacent to its open mouth to brace the walls thereof, which reinforce is set into a groove in the inner walls of the container, whereby the reinforce is retained 40 in place while bracing said walls.

My invention comprises novel details of 45 improvement and combinations of parts that will be more fully hereinafter set forth and then pointed out in the claims.

Reference is to be had to the accompanying 50 drawings forming part hereof, wherein,

Figure 1 is a side view of a container embodying my invention; Fig. 2 is an enlarged 55 plan view, the cover being removed; Fig. 3 is an enlarged cross section substantially on the line 3, 3, in Fig. 1; and Fig. 4 is a vertical section substantially on the line 4, 4, in Fig. 3.

Similar numerals of reference indicate 60 corresponding parts in the several views.

The numeral 1 indicates a container which may be in the form of a well known tin can having an open mouth, and at 2 is a cover having a flange 2^a adapted to fit 65 around the open mouth of the container in

an ordinary manner. Adjacent to the open mouth of the can and within the same is a reinforce 3, which may be made of wire and bent to snugly fit the walls of the container. The container illustrated is shown as having 60 an inner seam at 1^a which may be of any suitable form, and the ends of the reinforce 3 oppose the edges of the material of said seam, said ends being spaced apart to receive said seam between them, as illustrated in Fig. 3, thus resisting displacement of the reinforce within the container. When the reinforce 3 is fitted in a rectangular container said reinforce is so shaped that its portions 3^a fit snugly in a lengthwise manner for a suitable distance along and against 70 the inner faces of the walls of the container, and the portions 3^b intermediate the portions 3^a extend angularly with respect to the adjacent portions 3^a and thus in a direction somewhat diagonally with respect to and spaced from the corners of the container, whereby the parts 3^b serve as braces between the parts 3^a additionally strengthening the reinforce and serving to resist inward pressure thereon. The walls of the container are provided with an inner groove 4 which may be formed by beading the material of the container adjacent to its open 75 mouth, providing a seat for the reinforce 3 to retain the latter in position within the container. The reinforce may be placed within the container by pressing it therein, as the walls will expand sufficiently to enable the reinforce to enter the groove 4, and 80 the walls will contract upon the reinforce to retain the latter in position. The groove or bead 4 is shown in the walls of the container at a point below the flange of the cover, and the reinforce 3 is correspondingly located, 85 whereby such walls at the mouth of the container are rendered more rigid than they would be without the reinforce, and the material of the container around the open mouth is stiffened by the reinforce to resist 90 inward pressing of the walls, thereby to overcome objections inherent in certain kinds of tin cans, and particularly those of 95 rectangular variety, where the wall of the can adjacent the open mouth may be readily pressed in permitting thereby leakage or sifting of the contents of the can between such wall and the cover. With my improvements the stiffening of the wall of the can mouth serves to prevent such bending of the 100

105

110

wall, thereby to avoid such leakage, and this is particularly advantageous where tight fitting covers are applied at the mouths of tin cans, the flanges of which do not so readily press inwardly as the walls of the can.

My improvements are simple and cheap in construction, since the reinforce may be made of wire set in the groove or bead of the body of the container without requiring solder or other means to retain the reinforce in position, and also since the reinforce follows to some extent the contour of the container and does not necessarily extend transversely across the same, thereby not interfering with the ready filling or emptying of the container.

Having now described my invention what I claim is:—

1. A rectangular container having a beaded groove therein adjacent to its open mouth, and a reinforce within said groove and entirely within the container, portions of the reinforce extending along the inner walls of the container and portions of the

reinforce extending between the first named portions thereof and spaced from the corners of the container within the same to reinforce the walls between said corners.

2. A rectangular container having a beaded groove therein adjacent to its open mouth and substantially parallel thereto, and having an interior longitudinal seam along one wall, combined with a reinforce having portions in said groove bearing against the walls of the container and having its end portions opposing said seam, whereby the seam resists inward movement of said ends of the reinforce, said reinforce having portions between the first named portions at a distance from the corners of the container.

Signed at Passaic, in the county of Passaic and State of New Jersey, this 21st day of December, A. D. 1917.

MARCY J. DU BOIS.
